Primary Examiner—Janice E. Seeger*Attorney, Agent, or Firm*—Senniger, Powers, Leavitt & Roedel[57] **CLAIM**

The ornamental design for a bed frame, as shown and described.

DESCRIPTION

FIG. 1 is a front elevation of a bed frame showing my new design, the rear elevational view being identical thereto;

FIG. 2 is a top plan view thereof;

FIG. 3 is a left side elevational view thereof;

FIG. 4 is a right side elevational view thereof;

FIG. 5 is a bottom plan view thereof; and

FIG. 6 is a front elevation of the bed frame with a head section of the bed frame in an upright position;

FIG. 7 is a perspective view of a bed frame with a head section of the bed frame in an upright position; and,

FIG. 8 is a view of the inside of the footboard taken from the center of the bed frame.
